Primary Examiner — Rosemary K Tarcza*Assistant Examiner* — Sanjeev Paul(74) *Attorney, Agent, or Firm* — Muncy, Geissler, Olds & Lowe, P.C.(57) **CLAIM**

I claim, the ornamental design for a ski goggle frame, as shown and described.

DESCRIPTION

FIG. 1 is a perspective view of a ski goggle frame showing my present design;

FIG. 2 is a front view thereof;

FIG. 3 is a rear view thereof;

FIG. 4 is a left view thereof;

FIG. 5 is a right view thereof;

FIG. 6 is a top plan view thereof;

FIG. 7 is a bottom plan view thereof; and,

FIG. 8 is a perspective view thereof, shown in a state of use. The broken lines shown in FIG. 8 are for the purpose of illustrating environmental structure, and form no part of the claimed design.

1 Claim, 7 Drawing Sheets(56)
